United States Patent Office.

R. A. HILL, OF WASHINGTON, DISTRICT OF COLUMBIA.

Letters Patent No. 90,541, dated May 25, 1869.

IMPROVEMENT IN BRANCH STOP-COCKS FOR MAINS.

The Schedule referred to in these Letters Patent and making part of the same.

To all whom it may concern:

Be it known that I, R. A. HILL, of Washington, in the county of Washington, and District of Columbia, have invented a new and valuable Improvement in a Branch and Stop for Use of Fire-Plug; and I do hereby declare that the following is a full, clear, and exact description of the construction and operation of the same, reference being had to the annexed drawings, making a part of this specification, and to the letters and figures of reference marked thereon.

Figure 1, of the drawings, is a top plan view of my device.

Figure 2 is a longitudinal section of the same.

My invention relates to hydraulics; and

It consists mainly in constructing a four-way branch, to be placed at the centre of the four corners of streets, adapted to receive the water from each of the four street-mains, and, uniting the four streams into one, conduct the whole to a fire-plug on the pavement.

It also consists in constructing a hollow plunger, with openings, adapted to the four-way branch, and so arranged as to enable the operator to direct the course of the water into and out of the branch, or to stop it in the mains and from the fire-plug, simultaneously, at will.

The letter A, of the drawings, represents a cylinder, to which are attached the four arms B, in the manner shown, said arms being hollow, and adapted for connection, respectively, with the street-mains, and to receive the water therefrom.

The letter C is the plunger. This is made hollow, and adapted to fit in the inside of cylinder A, and rotate therein.

I make four openings in this plunger, one on each side, adapted to the water-capacity of arms B. These openings are marked D on the drawings.

The letter E is a cap, screwed on to the flange a, which flange forms the upper end of the plunger, as shown.

The letter F is a standard, attached to the top of the plunger, the top of which is made square, to adapt it for turning by a wrench.

This standard rotates inside of a collar, which forms the upper projection of the cap E, and which is marked e on the drawings.

On the inside of the top of cylinder A, and on the shoulder upon which the flange of the plunger rests, I

affix a pin; and I also cut out a portion of said flange, so that the plunger may move back and forth on said shoulder, and be stopped by such pin in both directions.

For the purpose of actuating the plunger, and thereby opening or closing the openings D, in addition to the square top of the standard above mentioned, I affix to said standard the ratchet-plate G, as shown. I further adjust a frame to the side and top of the cylinder A, and in said frame affix the standard s and the pinion u, as represented.

The upper end of standard s is made in a quadrangular form, and adapted for operation, in the usual manner, by a suitable wrench.

The letter H is a conducting-pipe, leading from the bottom of the cylinder A to the fire-plug on the pavement. I usually adjust it, with screws, by its flange, which corresponds, in size and shape, with the lower flange on said cylinder.

The capacity of this conducting-pipe is the same as that of the plunger, and its office is to conduct the water collected from the four street-mains to a fire-plug at the pavement of the street.

To operate my device, I turn either the standard F or s, by which means the openings in the plunger are brought opposite the openings in arms B, and thereby the water admitted; or said openings D are brought to the side of the cylinder, where there are no openings, and the water shut off.

My device is found to be of great value in streets where the supply of water is small, and one main inadequate to the requirements of firemen during a conflagration.

What I claim as my invention, and desire to secure by Letters Patent, is—

The hollow plunger C, with its openings D, the four-way branch, as described, the ratchet-plate G, standard s, pinion u, and conducting-pipe H, combined, arranged, and operating substantially as set forth.

In testimony that I claim the above, I have hereunto subscribed my name, in the presence of two witnesses.

R. A. HILL.
